UNITED STATES PATENT OFFICE.

JOHN J. HALLIHAN, OF CHARTLEY, MASSACHUSETTS, ASSIGNOR TO FREEMAN-DAUGHADAY CO., OF CHARTLEY, MASSACHUSETTS, A CORPORATION OF MASSACHUSETTS, ALSO DOING BUSINESS AS PROVIDENCE COLLAR BUTTON COMPANY, OF PROVIDENCE, RHODE ISLAND.

CLUTCH GUARD FOR PIN STEMS.

Application filed October 28, 1925. Serial No. 65,474.

This invention relates to a guard of the clutch type for pin stems and the like, and has for its object to provide such a guard, the body and operating members of which 5 are drawn up or formed from sheet stock to reduce the amount of metal employed and the cost of manufacture.

The invention further consists in the improved method of producing a clutch guard 10 of this character from sheet stock, which consists in drawing up the body portion from sheet stock into tubular form having a tapering end portion and drawing up the ball carrying and operating member from 15 sheet stock into tubular form and upsetting one end of the tube by an axial pressure to thicken the stock and provide a bearing or cage for the clutch balls; also pressing inwardly the side walls adjacent the folded 20 walls to form lateral guides for the balls mounted therein and inserting and operatively securing the tube in the body member.

With these and other objects in view, the invention consists of certain novel features 25 of construction, as will be more fully described, and particularly pointed out in the appended claims.

In the accompanying drawings:

Figure 1 is a side elevation showing my 30 improved clutch as applied to the stem of a scarf pin.

Figure 2 is a side elevation of the housing or body portion having been drawn from sheet stock into deep cup shape.

Figure 3 is a sectional elevation showing one end portion of the body as tapered and its opposite edge as beveled or drawn to a thin edge.

Figure 4 shows the operating tubular 40 member as drawn from sheet stock into deep cup shape with a flange at its lower edge.

Figure 5 shows the shank portion intermediate the ends of this deep cup as having been reduced leaving an enlarged head portion with the stock at the shoulder folded back upon itself, and the side walls of the head set inwardly toward each other.

Figure 6 shows the end of the head as 50 drilled to receive the pin stem and the sides of the head drilled to receive the clutch balls and the flange portion removed.

Figure 7 is a side elevation taken at right

angles to that of Figure 6, showing the lateral guides for the clutch balls and the shank opening of a size less than the diameter of 55 the balls to prevent them from dropping out of position when the pin stem is removed.

Figure 8 is a sectional side elevation illustrating the parts in assembled position.

Figure 9 is a sectional view on line 9—9 60 of Figure 8.

It is found in the practical construction and operation of a device of this character, of advantage from a manufacturing standpoint, to form the parts of a clutch guard 65 of this type of sheet stock by drawing and swaging operations rather than by the old method of forming the parts from solid stock; and the following is a detailed description of the present embodiment of my 70 invention and showing one means and describing one method by which these advantageous results may be produced:—

With reference to the drawings, 10 designates the body member of my improved 75 clutch guard, the same being drawn up into a deep cup-shaped member, as illustrated in Figure 2, the side walls 11 at one end of the cup being tapered for the purpose presently described; and the edges 12 at the opposite end of the body are preferably beveled outwardly as best shown in Figure 3, to render this edge more bendable, next the inner or operating member 13 is drawn up 80 from sheet stock, preferably by a drawing and swaging operation into a deep cup or tube having a flange 14 at one end, its upper end portion being tapered as at 15. The shank portion 16 of this member is then reduced, preferably by a hammering operation 85 between the tapered head portion 15 and the lower end portion 17, next I apply an endways pressure to crush or upset the head or end portion of this member thus 90 folding the stock of the walls back upon itself as at 18 forming a shoulder or thickened portion to serve as a bearing as at 19 for the clutch balls, I then press the side walls of the head portion inwardly as at 20 and drill slightly larger than the balls 100 through from side to side on a line with these inset portions thus providing adequate guiding walls or tracks for the clutch balls,

I then drill into the outer end of the head

removing the crushed-in stock 22 to form an opening 23 for the passage of the pin stem to be engaged by the clutch balls, I then cut off the flange 14 and bend the severed edges 24 inwardly into spherical shape as best illustrated in Figure 7, with a hole 25 at its lower end through which the pointed end of the pin stem may pass.

In assembling the parts I now place the 10 two balls 26 into the transverse opening or track in the head which now forms a cage for the balls, insert this tubular member carrying the balls into the body member 10 so that the balls will lie against the inner 15 tapering faces of the upper end of the body member. A spring 27 is then inserted into the body, one end 28 engaging the under side of the enlarged head portion of the tube and I then turn the beveled edge 12 of 20 this body inwardly to provide an abutment for the opposite end 29 of the spring. The device is now assembled and in position so that when the shank of the pin stem is 25 passed from the upper end down through the tube the clutch balls will act upon the inner tapering surface of the body upon being pressed inwardly by the spring to grip the shank of the pin stem and so prevent it from being withdrawn except when the lower 30 end portion 17 of the tube is drawn downwardly endwise relatively to the body thereby releasing the balls from engagement with the tapered walls permitting them to move outwardly and so release the pin stem 30 to 35 be freely withdrawn.

Having thus described one illustrative embodiment of my invention and the best mode known to me for carrying out my method, I desire it to be understood that although specific terms are employed, they 40 are used in a generic and descriptive sense and not for the purpose of limitation, the scope of the invention being defined and

limited only by the terms of the appended claims.

45

I claim:

1. A clutch guard for pin stems comprising a tubular body member formed of sheet stock with tapering walls at one end, a tubular pin stem receiving clutch operating member formed of sheet stock and having one end in said body the said end being upset and enlarged forming a ball cage with openings in its opposite side walls, clutch balls in said cage, and a spring pressing 50 said member inwardly to carry said balls into engagement with said inclined walls and by action of said walls into gripping engagement with the pin stem when positioned in the guard, and an integral hollow enlargement at the opposite end of said clutch member outside of said body for manual engagement for operating the same, the said enlargement having an opening in its end of a size substantially the size of the pin 55 stem to guide the same in its movement.

2. A clutch guard for pin stems comprising a tubular body member formed of sheet stock with tapering inner walls adjacent one end, and a tubular pin stem receiving clutch 70 operating member formed of sheet stock and having one end in said body, the said end being upset and enlarged, the side walls of this enlargement being set inwardly to provide lateral ball guides and having holes 75 through its opposite side walls at the ends of the guides, clutch balls in said guides, and a spring acting between said body and member to move the balls into engagement with the inclined inclosing wall causing them to 80 grip the pin stem, and an integral hollow spherical enlargement at the opposite end of the clutch member for manual engagement for operating the same.

In testimony whereof I affix my signature.
JOHN J. HALLIHAN.
